UNITED STATES PATENT OFFICE.

NICHOLAUS T. NILSSON, OF CHICAGO, ILLINOIS.

MOTION-PICTURE MECHANISM.

1,245,498.

Specification of Letters Patent.

Patented Nov. 6, 1917.

Application filed March 3, 1917. Serial No. 152,379.

To all whom it may concern:

Be it known that I, NICHOLAUS T. NILSSON, a citizen of the United States, and a resident of Chicago, in the county of Cook and State 5 of Illinois, have invented certain new and useful Improvements in Motion - Picture Mechanism, of which the following, when taken in connection with the drawings accompanying and forming a part hereof, is a 10 specification.

This invention relates to mechanism adapted to be installed in a cabinet arranged to display projected motion pictures; said cabinet designed to be used in homes and in public 15 places before small audiences; and to use the well known film pictures which are now employed, in motion picture machines.

The object of this invention is to obtain mechanism which, when installed in a cabinet, 20 may be manipulated from one side of the cabinet to insert or remove the film used and also to adjust the film so that the picture projected therefrom will be focused and directed to its determined position on a 25 screen, curtain or plate.

A further object is to obtain mechanism of the kind named which will consist of few parts or members so connected as not to get out of order or adjustment.

30 And a further object is to obtain mechanism of the kind named which is readily understood and operable by persons not particularly skilled in motion picture machines.

I have illustrated mechanism embodying 35 this invention in the drawings accompanying and forming a part hereof in which—

Figure 1 is a side elevation, and

Fig. 2, is a vertical section on line 2—2 of Fig. 1 viewed in the direction indicated by 40 the arrows.

A reference character applied to designate a given part indicates said part throughout the several figures of the drawing wherever the same appears.

45 A, Fig. 2 represents a portion of a side wall of a cabinet.

B, represents a base which is secured to side wall A.

C, represents a standard extending from 50 base B, to and supporting bearings D, and E; and C' represents a standard also extending from base B to and supporting a film actuating sprocket wheel and related parts.

F, represents a shaft rotatably mounted in 55 bearings, D, d.

G represents the shutter shaft of the mech-

anism and is illustrated as rotatably mounted in bearing E. H, represents a shutter which is provided with suitable openings, as 60 h, and is rigidly secured to the upper, and squared end g, of shaft G. I, J, are beveled gear wheels which are rigidly secured to shafts F, and G respectively, so as to intermesh.

K represents a wheel or pulley rigidly secured to shaft F. A belt, (not shown) on wheel K drives said wheel, thereby rotating the shaft F, which is the driving shaft turning the shaft G, shutter H and the several mechanisms about to be described.

M is a beater which is adjustably mounted on shaft F and actuated thereby to give a step by step movement to the picture film (Z) when the machine is operated.

70 Beater M, may be turned on shaft F to adjust it relative to said shaft and shutter H, by means of the manually operable wheel m (mounted on arm m'), and gears m'' m'''.

Gears m'' and m''' intermesh and said gear m''' is attached to the beater M by 80 screw m'''.

N is a gear which is rigidly attached to shaft F.

O is an idler loosely mounted on spindle O' and provided with gear teeth intermeshing with gears N and P, to communicate motion of said gear N to gear P.

Gear P is a member of the mechanism which draws the picture film Z from spool X and delivers it to spool Y. y is a belt passing over the pulley L and pulley y' to actuate spool Y.

The connection between pulley y' and spool Y is by means of the ordinary friction disks, whereby as the spool is filled no undue strain is put on the film and at the same time it is tightly wound on the spool; but as said connection forms no part of this invention it is not illustrated or described.

Z' is an idler for film Z.

100 The film actuating mechanism is mounted on the spindle R, and consists of drum Q, which is provided with sprocket teeth q, the rollers S, S, (rotatably mounted in frames T), and said frames. The gear P is also 105 loosely mounted on spindle R and is rigidly secured to the drum Q.

Frame T consists of a base t, which is provided with hub t', the members t'', which are hinged to base t by the spindles U, and 110 the spring u.

The rollers S are rotatably mounted in

members t'' . The spindle R is secured in hub t'' . The hub t' is inserted in the end of standard C' and is adjustable by turning it to one or the other direction and secured in 5 its angularly adjusted position in said standard, as by set screw u' .

To adjust the picture film so that the pictures projected therefrom will appear between determined lines on the curtain or 10 screen, the hub t' of frame T is turned in the end of the standard C' to move said frame say from the position thereof which is illustrated by full lines in Fig. 1 toward, and if necessary to the position thereof which is 15 indicated by broken lines in said figure.

The spring u yieldingly holds members t'' in the positions which are illustrated in the drawing, thereby holding the film, Z, (Fig. 1), on the sprocket teeth q ; but said members 20 may be turned on pintle U, to permit the removal of said film from the sprocket wheel and the placing of an additional one thereon.

V are projecting lenses, V' a condenser 25 and V'' a lamp. W is a film guide comprising two members which are pivotally joined by pintle W' and the upper one thereof yieldingly held closed on to the lower one by spring W'', (see Fig. 2). The members 30 of guide W are provided with apertures W''', which register when the members thereof are closed, and with the recesses W'''', (see Fig. 2) through which the film extends.

35 The members of guide W are separated by turning the upper one of said members on pintle W' against the resiliency of spring W'' when it is desired to insert a film in or to remove a film from said guide.

40 U' is an extension of bearing D, which is rigidly attached to said bearing, to form the supporting member of the lens V, condenser V', and guide W.

U'' is a reflecting mirror and V''' V'''' 45 are lines respectively indicating the direction of a ray of light from lens V to mirror U'' and from thence to a screen or curtain.

It will be observed that the film Z is drawn 50 from the spool X by sprocket wheel Q, (said film passing over the idler Z' which is positioned between said sprocket wheel and spool), and from said sprocket wheel the film is looped around the lamp V'', and condenser V' before entering guide W; and 55 said film, after leaving said guide W, passes over the beater M to said sprocket wheel Q, and from thence to spool Y, on which it is wound by belt y turning said spool. The film being drawn from spool X and feed 60 to spool Y by a single sprocket wheel, (Q), whatever size is given to the loop of the film between said sprocket wheel and said guide, as last above described, will remain constant during the entire operation of

transferring the film from said spool X to 65 spool Y.

The belt driving pulley K is designed to be driven by an electric motor and after a film has been placed on the spools X, Y, sprocket wheel Q and in guide W, as hereinbefore described, the lamp V'' lighted condenser V' and lens V adjusted, and focused, with the member T carrying rollers S adjusted to direct the projection of the film to proper position on the screen, said motor 75 may be started and the motion pictures desired thereby obtained.

I claim:

1. Motion picture mechanism comprising 80 a spindle, a sprocket member adapted to actuate a picture film rotatably mounted on said spindle and a gear secured to said sprocket member, in combination with a standard, a roller supporting member consisting of a base mounted on said standard 85 concentric with said sprocket wheel, and roller carriers pivotally attached to said base, rollers rotatably mounted in said carriers to operatively co-act with said sprocket member, means to yieldingly hold said carriers with said rollers in operative position, said base movable in said standard to obtain angular adjustment of said rollers on said sprocket member, and means to retain said base in its adjusted position. 95

2. Motion picture mechanism comprising 100 a rotatably mounted shaft, a beater on said shaft a gear rigidly secured to said shaft, a spindle, a sprocket member adapted to actuate a picture film rotatably mounted on 105 said spindle, a gear secured to said sprocket member, and an additional gear intermeshing with said first named gears, in combination with a standard, a roller supporting member consisting of a base mounted on said 110 standard concentric with said sprocket wheel and roller carriers pivotally attached to said base, rollers rotatably mounted in said carriers to operatively co-act with said sprocket member, means to yieldingly hold 115 said carriers with said rollers in operative position, said base movable in said standard to obtain angular adjustment of said rollers, on said sprocket member and means to retain said base in its adjusted position. 115

3. Motion picture mechanism comprising 120 a spindle, a sprocket member adapted to have a picture film in operative contact therewith on opposite sides thereof, and actuate said film in opposite directions, rotatably mounted on said spindle and a gear secured to said sprocket member, in combination with a guide for said film positioned to receive said film between the points of contact thereof with said sprocket 125 wheel, a standard supporting member consisting of a base mounted on said standard concentric with said sprocket wheel and

roller carriers pivotally attached to said base, rollers rotatably mounted in said carriers to operatively co-act with said sprocket member, means to yieldingly hold said carriers with said rollers in operative position, said base movable in said standard to obtain angular adjustment of said rollers, on said sprocket member and means to retain said base in its adjusted position.

10 4. Motion picture mechanism comprising a rotatably mounted shaft, a beater and a sprocket mechanism respectively connected to said shaft to be actuated thereby, and film spools, in combination with a film

guide, a lamp, a condenser and a lens, said 15 sprocket mechanism arranged to draw a film from one of said spools and to deliver said film around said lamp and condenser to said guide, and to operatively co-act with said beater to draw said film through said guide 20 in a step by step movement and deliver it to the other of said spools, and said sprocket mechanism adjustable to position said film in said guide.

NICHOLAUS T. NILSSON.

In the presence of—

CHARLES TURNER BROWN,
J. SCUDDER.
